UNITED STATES PATENT OFFICE.

EMIL KLEBERT, OF KARLSHORST, NEAR BERLIN, GERMANY, ASSIGNOR TO JULIUS
PINTSCH AKT.-GES., OF BERLIN, GERMANY.

POROUS CHARGE FOR CONTAINERS SERVING FOR STORAGE OF EXPLOSIVE GASES
DISSOLVED IN LIQUIDS, AS, FOR INSTANCE, ACETYLENE.

1,419,862.

Specification of Letters Patent. Patented June 13, 1922.

No Drawing.

Application filed January 3, 1920. Serial No. 349,324.

To all whom it may concern:

Be it known that I, EMIL KLEBERT, a subject of the Republic of Germany, residing at Karlshorst, near Berlin, Germany, have 5 invented certain new and useful Improvements in porous charge for containers serving for storage of explosive gases dissolved in liquids, as, for instance, acetylene (for which application has been filed in Germany 10 May 21, 1914, Number 291,141), of which the following is a specification.

The gas-containers for acetylene which is dissolved in liquids, for instance acetone, have been filled up-to-now either with a 15 stone-like mass or material of a grained or porous nature. The employment of highly homogeneous bodies entails the disadvantage, that it is impossible to undertake an inspection of the interior of the container 20 or a test of the water-pressure to be repeated later on, without totally destroying the aforesaid bodies. If, on the other hand the charge consists of grained porous material as for instance, pumice-stone, silicious 25 marl, charcoal or clay, the danger has been created that, on account of the permanent shaking movement, for instance, when being transported, hollow spaces are formed within 30 the charge, which constitute a dangerous factor in regard to the continuation of ex-

plosions. It has already been suggested to employ as charge a material such as charcoal.

In order to create a certain, interior pressure and elasticity within the charge, the 35 admixture of naturally existing, porous, elastic materials as for instance, cork, elder-pith, sponge or such like, which swell when the fluid for dissolving the acetylene is 40 added, has proved quite sufficient.

If these porous materials capable of swelling are mixed with the known non-elastic, porous masses, and placed in the containers in a dry condition, an interior pressure will be created through the swelling of the 45 component parts of the charge, when the dissolving fluid is admitted, which holds the different parts of the charge together under increased friction, thereby preventing their displacement to each other and finally fills 50 up any hollow spaces existing within the charge on account of their increase of volume.

Having fully described my invention, I 55 claim:

A porous charge for acetylene gas containers, consisting of a mixture of crushed charcoal and cork.

In testimony whereof I affix my signature.

EMIL KLEBERT.
